(57) **CLAIM**

The ornamental design for a bottle opener lure, as shown and described.

DESCRIPTION

FIG. 1 is a top perspective view of a bottle opener lure in my new design.

FIG. 2 is a top plan view thereof, the bottom plan view being the same.

FIG. 3 is a first side plan view thereof, the second side plan view being the same.

FIG. 4 is a third side plan view thereof.

FIG. 5 is a fourth side plan view thereof.

FIG. 6 is a cross section view thereof taken through section line 6-6 shown in FIG. 2; and,

FIG. 7 is a cross section view thereof taken through section line 7-7 shown in FIG. 2.

The broken lines in the figures depict the bounds of the claimed design and form no part thereof.

All surface not shown form no part of the claimed design.
